Primary Examiner — Eric L Goodman*Assistant Examiner* — Sanjeev Paul(74) *Attorney, Agent, or Firm* — Sheppard, Mullin, Richter & Hampton LLP(57) **CLAIM**

We claim the ornamental design for a pillow, as shown and described.

DESCRIPTION

FIG. 1 is a front, right perspective view of a pillow embodying our new design;

FIG. 2 is a top plan view of the pillow;

FIG. 3 is a bottom plan view of the pillow;

FIG. 4 is a right side elevational view of the pillow;

FIG. 5 is a left side elevational view of the pillow;

FIG. 6 is a rear side elevational view of the pillow; and,

FIG. 7 is a front side elevational view of the pillow.

The broken lines in FIGS. 1, 2, 4, 5 and 7 represent stitching that forms part of the claimed design.

1 Claim, 4 Drawing Sheets(56)
